UNITED STATES PATENT OFFICE.

DANIEL A. SMITH, OF DRUMMOND, MARYLAND, AND JOHN P. MANN, OF WASHINGTON, DISTRICT OF COLUMBIA, ASSIGNEES TO DISTRICT OF COLUMBIA PAPER MANUFACTURING COMPANY, OF WASHINGTON, DISTRICT OF COLUMBIA, A CORPORATION OF VIRGINIA.

PAPER-MAKING MACHINE.

992,693.

Specification of Letters Patent. Patented May 16, 1911.

Application filed May 5, 1910. Serial No. 559,569.

To all whom it may concern:

Be it known that we, DANIEL A. SMITH, of Drummond, in the county of Montgomery and State of Maryland, and JOHN P. MANN, 5 of Washington, District of Columbia, citizens of the United States, have invented certain new and useful Improvements in Paper-Making Machines, of which the following is a full and complete specification.

10 Our invention is an improvement in paper-making machines, and is more especially an attachment adapted to operate on the paper stock during the "making" of the paper, so that the finished product will possess certain peculiar characteristics or ornamentation.

Our invention relates more especially to an attachment to Fourdrinier machines, and the primary object of the same is to provide 20 an attachment which may be readily applied without altering any part of the construction and arrangement of such a machine, and will operate on the surface of the wet web or layer of pulp somewhere between the 25 slices and couch-rolls so as to disturb the fibers in such manner that the finished paper will have a peculiar ornamentation or mottled appearance in the nature of a watermark. In the present instance we accomplish 30 this object by the application of a drag, which imposes more or less pressure upon the surface of the wet web or layer of pulp while the latter is undergoing the felting action due to the shake of the wire.

35 In the following description we have set forth the particular construction of the present device, its operation, and practical advantages, and what we wish to claim as our invention, and desire to fully protect by 40 Letters-Patent is particularly stated in the appended claims.

In the accompanying drawings, which form a part of this specification: Figure 1 is a side view of a conventional Fourdrinier 45 paper-making machine, showing the application of our invention thereto. Fig. 2 is a detail plan view of the attachment, as applied. Fig. 3 is a sectional view through the attachment, the paper-stock and the wire.

50 Like numerals of reference indicate like parts in all the figures of the drawings.

In the present instance we have shown the attachment as applied to a conventional form of Fourdrinier machine, and inasmuch as our invention does not contemplate a re-organization of such machine, or rather is more in the nature of an attachment to the same, it is not deemed necessary herein to describe in accurate or precise detail all of the constituent parts of the machine, but it 55 will be sufficient for our present purpose to merely refer, in a general way, to those parts which operate in conjunction with our invention. Furthermore, it will be understood that we do not in the present instance 60 claim as our invention anything in the construction of the machine itself, aside from the attachment, which latter constitutes the 65 basis of our claims, as hereinafter set forth.

In the conventional form of Fourdrinier 70 paper-making machines the frame, as 5, is supported in a suitable manner so that a lateral vibratory motion may be imparted, for instance at its ends by pivoted standards or posts 6, 6, and intermediately by several uprights or bars 7, which latter may be threaded, as shown, for the purpose of adjustment of the bearing-brackets 8 which support the guide-rollers 9. At one end of the frame is the usual pulp-receiving trough 10, at the 75 forward end of which are the slice-bars 11, 11, and at this end of the frame there is also the breast roll 12 around which the wire 13 passes to the tube-rolls 14, said wire passing from the tube-rolls 14 over suction-boxes 80 15 to the couch-rolls 16. The machine is also provided with a deckle-strap 17 at each side, which passes over suitable guide-rollers, as 18, and over a pair of equalizing rollers 19, as is usual. In the drawings we 85 have also shown the machine as provided with a drain trough, 30, suitably supported beneath the upper stretch of the wire, the latter passing beneath said trough and under and over the guide-rollers 9 in the customary manner.

The operation of a Fourdrinier machine such as shown in the drawings, and above briefly described, will be readily understood by those skilled in the art of paper-making, for the paper pulp or stock from the receiving-trough 10 is fed or distributed on to the 90 95 100

wire 13 by means of the slices 11, and as it is carried along by said wire over the tube-rolls 14 it is subjected to a shake so that the fibers of the floating web will undergo the 5 felting action, the water being extracted by the suction-boxes 15 so that the web will be in proper condition for the action of other parts of the paper-making machine, as will be understood.

16 The machine shown is only one form of Fourdrinier machine, but it will be apparent, hereinafter, that we may apply our invention to many different forms of paper-making machines.

15 In carrying out our invention we subject the paper stock or layer of pulp to the effect of a drag which acts upon the surface thereof, in the present instance the uppermost surface, so as to disturb or roll the fibers to 20 a more or less extent, whereby they are massed or grouped irregularly and so that the distinct masses or groups so formed will not be obliterated by the subsequent or continued felting action of the shaking wire.

25 Of course, as will be obvious this massing, grouping, or rolling of the fibers of the paper pulp may be produced by the application of any device which operates to drag over the surface of the layer of pulp, and as 30 will be apparent, also, the manner in which the fibers are disturbed or effected will depend upon the nature of the drag, as well as the weight of the same. In the present instance we employ a strip or sheet of material, 21, as felt, and support one end of the same above the layer of pulp, 4, so that the other or free end of said strip or sheet will lie upon the layer of pulp and drag over the surface of the same. If desired 40 additional weight may be given to that portion of the strip or sheet which engages the layer of pulp, as for instance by means of a strip 22, attached to said strip or sheet near the outer or free end of the same, as shown 45 in the drawings.

The drag or strip of felt may be supported in any suitable manner, a simple form being shown, which consists in attaching one end of the felt strip to a cross-bar 23, with the 50 ends of the latter projecting sufficiently to rest upon the top-rail 5^a at each side of the supporting-frame of the machine, the ends of the cross-bar being each engaged by a bracket-plate 24, or any other suitable means 55 for holding the bar in place. The bracket-plates are secured upon the top-rails by screws 25, so that said brackets may be shifted to any point along the rails from the slice-bars to the couch-rolls, for the location 60 of the device at any desired point with respect to the "making" of the paper. In the practice of our invention we have found that good results are obtained by placing the drag at a point where the wet web or 65 layer of pulp has undergone the felting ac-

tion to some extent, rather than close up to the slice-bars.

The drag may be stationary, but we prefer that it be so mounted on the machine as to shake with the wire and layer of pulp 70 carried thereby.

As hereinbefore explained, the operation of the drag results in rolling or massing some of the fibers in irregular lines or groups, somewhat in the manner indicated 75 in Fig. 2 of the drawings, and as these irregular lines or groups are not obliterated by the subsequent finishing or calendering the paper produced has an ornamental surface, or is mottled or grained in the nature of a 80 water-mark, such mottling or graining varying to a considerable extent but retaining certain peculiar characteristics which cannot be obtained in any other way, so far as we are aware.

Having thus described our invention, we claim:

1. An attachment for paper-making machines, comprising means engaging a surface of the layer of pulp and dragging 90 thereover to displace and aggregate some of the fibers, substantially as shown and for the purpose set forth.

2. An attachment for Fourdrinier paper-making machines comprising a strip of material resting upon the moving layer of pulp 95 so as to drag thereover, substantially as shown and for the purpose set forth.

3. In a Fourdrinier paper-making machine, the combination with the moving 100 wire carrying a layer of pulp, of a strip of flexible material, and means for supporting said strip so that a portion thereof will drag over the surface of the layer of pulp, substantially as shown and for the purpose set 105 forth.

4. In a Fourdrinier paper-making machine, the combination with the moving wire carrying a layer of pulp, of a strip of flexible fabric supported at one end so that the 110 free end thereof will drag over the layer of pulp, substantially as shown and for the purpose set forth.

5. In a Fourdrinier paper-making machine, the combination with the moving wire 115 carrying a layer of pulp, of a supporting-bar, and a strip of flexible material attached at one end to the supporting-bar and having its free end resting upon the layer of pulp so as to drag thereover, substantially as 120 shown and for the purpose set forth.

6. In a Fourdrinier paper-making machine, the combination with the moving wire carrying a layer of pulp, of a supporting-bar, a fabric strip attached to the supporting-bar so that the free portion of said strip 125 will drag over the layer of pulp, and means for holding the supporting-bar rigidly in place, substantially as shown and for the purpose set forth.

7. In a Fourdrinier paper-making machine, the combination with the top-rails, moving wire carrying a layer of pulp, of a supporting-bar resting at its ends upon the top-rails, a strip of material attached to the supporting-bar so that the free portion of said strip will drag over the layer of pulp, and bracket-plates attached to the top-rails to hold the supporting-bar in place, substantially as shown and described.
